US00D779522S

(12) **United States Design Patent** (10) **Patent No.:** **US D779,522 S**
Ahadi et al. (45) **Date of Patent:** **** Feb. 21, 2017**

(54) **DISPLAY SCREEN OR PORTION THEREOF WITH GRAPHICAL USER INTERFACE**

(71) Applicant: **ADP, LLC**, Roseland, NJ (US)

(72) Inventors: **Masheed Ahadi**, New York, NY (US); **Alain Brown**, Brooklyn, NY (US); **Matt Herman**, Hoboken, NJ (US); **Agatha Kurjanowicz**, New York, NY (US); **Jason Lovelace**, Montclair, NJ (US); **Lohit J. Sarma**, New York, NY (US); **Omar Scott**, New York, NY (US); **Zachary A. M. Skolnik**, New York, NY (US)

(73) Assignee: **ADP, LLC**, Roseland, NJ (US)

(**) Term: **14 Years**

(21) Appl. No.: **29/521,026**

(22) Filed: **Mar. 19, 2015**

(51) LOC (10) Cl. **14-04**

(52) U.S. Cl.

USPC **D14/486**

(58) **Field of Classification Search**

USPC **D14/485-495**

CPC **G06F 17/246; G06F 17/30056; H04N 1/00198; H04N 21/234336**

See application file for complete search history.

(57) **CLAIM**

We claim the ornamental design for a display screen or portion thereof with graphical user interface, as shown and described.

DESCRIPTION

The FIGURE is a front view of a display screen or portion thereof with a graphical user interface.

The outermost broken line rectangle showing of the display screen and all other broken lines showing portions of the graphical user interface are included for the purpose of illustrating portions of the article and form no part of the claimed design.
